FIREARM MAGAZINE CONSTRUCTION

Harold D. Allyn, Springfield, Mass.

Application November 19, 1957, Serial No. 697,422

4 Claims. (Cl. 42—18)

This invention relates to new and useful improvements in that class of breech-loading firearms in which the breech-piece consists of a longitudinally-sliding bolt and a magazine is provided for the containment of one or a plurality of cartridges or shells, each to be successively introduced in front of the open breech-piece and carried into the chamber of the barrel by the closing movement thereof.

The invention relates generally to magazine firearms and to the method of feeding cartridges or shells thereinto and the general object hereof is to provide improvements in the method of feeding cartridges or shells to the magazine and feeding same therefrom to the breech and also to provide other improvements in various details of the magazines and feeding systems of firearms.

It is directed specifically to a novel and unique firearm construction embodying the general features of a bottom-loading box-type magazine.

The invention relates more particularly to a follower mechanism operable within a magazine chamber of a firearm, which chamber is adapted to receive a single row of cartridges or shells or a double row thereof wherein the cartridges are arranged in interengaging staggered relation.

The bottom loading feature hereof makes loading easier, particularly when applied to a bolt action-type of rifle. This is especially true of a firearm which is equipped with a low mounted telescopic sight.

Too, it enables the hunter to fill a partially charged magazine in the field, when he may be expecting to jump game, without rendering the gun inoperative by the necessities of opening the bolt and of charging the magazine from the top, as in the conventional manner.

As applied to the Mauser type of bolt action firearm, the invention hereof offers the sportsman a choice of three methods of charging the magazine: (1) He may charge singly from the top with the bolt open (a method presently used by sportsmen); (2) he may charge with the well-known Mauser type charger clip (a system preferred by military personnel); or (3) he may charge singly from a loading port in the bottom of the firearm.

The invention hereof offers various advantages in firearms of the types contemplated. In the first place, the firearm can be loaded or reloaded while in the firing position, and, in the second place, it can be loaded from the top as with a clip, from the top where the cartridges are loaded one at a time, or from the bottom where the cartridges can be loaded one at a time.

In follower mechanisms of certain prior art which function to feed the cartridges of a stack thereof, wherein said cartridges are arranged in a double row in the known interengaging staggered relationship throughout their vertical movement upwardly from the moment of their loading into the magazine chamber to the moment of their discharge therefrom, it has not always been possible to adapt the follower to support or to engage the lowermost cartridge of each row of the stack before the

2

total exhaustion of the cartridges from the chamber, wherefore jamming of the firearm has frequently resulted. In this invention, the follower is adapted to accommodate itself to different relative positions of the lowermost cartridges of each row of the double row, due to variations arising from permissible tolerances in the dimensions of the cartridges and in the components of the follower mechanism.

Other advantages of the invention reside in its simplicity of construction, in its efficient and dependable operation, and in its adaptability to economical manufacture.

The foregoing and other objects and advantages hereof will become more apparent as the description proceeds. Same reside in the details of construction and operations to be more fully described and claimed hereinafter.

Although this invention will be described and illustrated with particular reference to a Mauser type rifle and a shotgun, it should be appreciated that its utility and application extend beyond the particular type of firearm illustrated and comprehend the useful and novel features set forth when incorporated in other types of weapons. That is, the invention basically contemplates certain new fundamental principles of design, which principles can be equally well applied to various types of firearms.

The invention comprises the features hereinafter fully described and particularly pointed out in the following description, annexed drawings and claims, setting forth in detail certain illustrative embodiments of the invention, these being indicative, however, of but a few of the various ways in which the principle of the invention may be employed.

In said annexed drawings:

Fig. 1 is a sectional view of the midsection of a firearm showing a basic rear-pivot bottom-loading magazine of the invention, only so much of the firearm being shown as is necessary to the understanding of the general features of my invention;

Fig. 2 is a sectional view on the line 2—2 of Fig. 1, the breech bolt having been retracted to the rear or open position in the receiver;

Fig. 3 is a sectional view on the line 3—3 of Fig. 1;

Fig. 4 is an outside view of the breech section of a rifle of the Mauser type showing a cartridge being loaded into one form of the magazine chamber of my invention;

Fig. 5 is a bottom plan view of the firearm shown in Fig. 4;

Fig. 6 is a view, similar to Fig. 4, but with the stock thereof removed for the sake of clarity and with a plurality of cartridges stacked within the magazine;

Fig. 7 is a fragmentary outside view of the lower portion of the breech section of the firearm shown in Fig. 5, showing the cartridges being emptied from the magazine through the bottom thereof;

Fig. 8 is a view, similar to Fig. 6, but without cartridges stacked within the magazine, and with the bolt in the open position;

Fig. 9 is a partial sectional view through the upper portion of the receiver and the breech bolt and the magazine follower wherein the breech bolt is closed, the magazine is empty, and the magazine follower is in its upper position with the medial rib thereof embracing the underside of the breech bolt.

Fig. 10 is a partial sectional view on the line 10—10 of Fig. 8 showing the port shutoff lever and the port shutoff pivot pin, the breech bolt being in the open position;

Fig. 11 is a full sectional view on the line 11—11 of Fig. 6 showing the magazine fully charged;

Fig. 12 is a sectional view on the line 12—12 of Fig. 8 showing the magazine follower arm pivot pin and the magazine follower spring, the port shutoff being in the upward position, the breech bolt being closed, and the magazine being empty;

Fig. 13 is a perspective view of the magazine follower and magazine follower arm;

Fig. 14 is a fragmentary view of the lower portion of the firearm shown in Fig. 6 but with a Mauser type magazine spring in place of a mouse trap type spring;

Fig. 15 is an outside view of the breech section of a shotgun showing shells being loaded into a modified form of the magazine of my invention; and

Fig. 16 is a bottom plan view on the section 16—16 of Fig. 15 showing a bottom view of said modified form of magazine.

In the following description and claims, various details will be identified by specific names for convenience. These names however are intended to be as generic in their application as the art will permit.

Referring in detail to the drawings forming a part of this specification, in which drawings similar characters of reference indicate corresponding parts in the several views, and referring more particularly to the preferred form of my invention selected for illustrative purposes, I have shown in Fig. 1, a basic or simplified version of a magazine in association with a simplified breech action of a rifle in order that the general relation and utility of the components may be better understood.

Referring to Fig. 1, 10 represents the barrel, 12 the receiver, in threaded engagement with the barrel, 14 the breech bolt slidably receivable within a longitudinally disposed breech bolt chamber in the receiver, 16 the extractor, and 18 the stock. The breech bolt 14 is in the forward or locked position and may be reciprocated rearwardly relative to and within the receiver 12, during which interval the operations of loading cartridges into and unloading cartridges from the barrel chamber ensue, all as is well-known.

A magazine chamber is provided by a vertically disposed recess or cavity which extends through the receiver 12 downwardly of the breech bolt chamber, with which it is in communication, so as to provide what will be referred to as a perpendicular feed so far as the principles of operation are concerned.

The magazine chamber includes a box like metallic casing, generally designated by the numeral 20, which casing is oblong in its horizontal cross section and is defined by vertically disposed walls including a forward wall 22, a pair of spaced opposite side walls 24 and 24 and a rearward wall 26, all of which walls are interconnected and may be secured to the receiver by any conventional means, with the upper end of the magazine chamber being open to afford communication with the breech bolt chamber.

The lower end of the magazine chamber may be closed as by a bottom plate 28 which may be fixed to the vertical walls in the usual manner. If desired, the lower end thereof may be left open with the bottom plate being omitted and with the follower itself (subsequently to be described) serving as the only closure therat.

The rearward wall 26 does not extend downwardly so as to contact the bottom plate 28 but rather stops thereabove so as to provide what will be defined as a lower loading opening or port 30, as shown, and through which cartridges C may be inserted into the magazine in seriatim and arranged therein one above another in a single vertical column in the well-known manner. The cartridges may be forced through the opening 30 as by the thumb T of the operator's hand.

Pivotedly mounted between the aforesaid side walls 24 and 24 by means of a transversely extending follower pivot pin 32 receivable in appropriately aligned openings in the side walls 24 and 24 is a vertically movable magazine follower 34. Same is adapted to engage

the lowermost cartridge of the column thereof as said cartridge is inserted into the magazine through the loading port 30. The follower urges the stack of cartridges upwardly during the storing operation. Subsequently, as the uppermost cartridge of the stack thereof is removed from the top of said stack, the follower continues to move vertically upwardly. Same is actuated by the upward urging of a vertically movable magazine follower spring 36 disposed beneath the follower 34 and held relative to the side walls 24 of the magazine chamber by means of transversely extending ears 38 extending into the side walls. See Fig. 3.

The free forward end portion 29 of the follower may be so bent that, upon the depression of the follower, it extends through a suitable opening 29' in the bottom plate 28. See Fig. 1.

It will be observed that the follower 34 is depressed by each successive cartridge as same is inserted into the magazine through the lower loading port 30. When released, following loading, the follower moves upwardly against the lowermost cartridge of the stack thereof to embrace same snugly whereby the cartridges are prevented from escaping rearwardly and downwardly through the lower loading port.

At the top side of the side walls 24 and 24, magazine ears 25 of conventional design may be provided or, in lieu thereof, magazine feed cuts (not shown) may be provided in the receiver 12, in the well-known manner. The ears or the feed cuts, as the case may be, assist in the feeding of the cartridges from the magazine upwardly into the chamber in the well-known manner.

The operating mechanism of the breech bolt is conventional. When same is reciprocated forwardly, the topmost cartridge C is urged into the breech bolt rim cuts (not shown) on the forward face of the breech bolt for subsequent transfer to the barrel chamber.

After firing of the piece has been effected, the recoil action of the breech bolt ensues. Of course, the breech bolt can also be moved rearwardly by manual action. Upon the subsequent forward reciprocation of the breech bolt, another cartridge is withdrawn from the magazine chamber and is advanced into the firing chamber. Such action continues until the magazine chamber is emptied.

In Fig. 1, a lowermost cartridge is shown as being loaded into the lower rearward end of the magazine chamber through the loading port 30. The follower has been depressed by the insertion of the said lowermost cartridge into the magazine chamber. The breech bolt is shown as in the closed position.

In Fig. 2, however, the magazine is illustrated as being fully charged. The breech bolt is not shown therein, same having been reciprocated to its rearmost position relative to the receiver.

Referring now to Fig. 4, I have shown the breech section of a Mauser type rifle wherein a cartridge C is illustrated as being loaded by a thumb T' of an operator into a magazine chamber according to one form of my invention.

Herein 110 represents the barrel, 112 the receiver, 114 the breech bolt slidably receivable within the receiver, 115 the bolt handle, 118 the stock, 119 the trigger and 119' the trigger guard. The barrel 110 is threadedly secured to the forward end of the receiver 112 in the well-known manner. The breech bolt 114 is of the upturn-and-pull-back type.

A magazine is provided in the upper portion of the guard, as in the form hereinabove described, and comprises a vertically disposed walled chamber which extends upwardly into the receiver. The upper end of the magazine chamber is open and communicates with the breech bolt chamber thereabove. The lower end of the magazine chamber is likewise open and is provided with a bottom floor plate member 140 which is hinged at its rearward extremity by means of a follower arm pivot pin 142 extending transversely through the trigger guard 119' and

through aligned openings in spaced opposite side walls 141 extending upwardly from the member 140, as shown. The forward extremity of the bottom floor plate member is engageable with a swingable clamping member 144 which is held in pivotal relation with the receiver by means of a clamping shoulder screw 146 so as to be movable into and out of clamping engagement with the bottom floor plate member.

A pin or stop 145 depends vertically downwardly from the guard to limit the swinging movement of the clamping member 144 and to insure the stopping thereof at its optimum clamping position.

A release catch, pivoted to the forward portion of the guard on a horizontal axis or horizontally-slidable thereto, could be used in lieu of the clamping member 144 as illustrated and described.

When so clamped to the guard, the bottom floor plate member 140 serves to close off the bottom of the magazine chamber. When unclamped, the bottom floor member is pivoted downwardly upon the follower arm pivot pin 142 by means of a spring subsequently to be described.

One side of the trigger guard and the lower portion of the adjacent side of the stock are cut away to provide a lower loading opening or port 130 therethrough (best shown in Figs. 4 and 5) which affords entrance from the outside of the firearm into the magazine chamber.

Through this port or opening 130, the cartridges C may be inserted in seriatim into the magazine chamber.

In this instance, as best shown in the cutaway view, Fig. 6, the magazine chamber may be of such width as to provide a means for receiving two rows of staggered cartridges in the well-known manner.

Pivottally mounted within a slot in the bifurcated forward portion of the trigger guard 119, by means of the aforescribed follower arm pin 142, is a vertically movable magazine follower arm 134.

The follower arm 134 is provided with a hump 135 which supports the cartridges when the magazine is nearly full.

At the forward extremity of the follower arm 134, preferably called a primary arm portion of the follower, is a forwardly extending complementary follower 150, preferably called a secondary arm portion of the follower, which is pivotally fixed to the member 134 by means of a transversely extending follower pivot pin 152, as shown.

Fixed to the underside of the primary arm portion 134 is a stop 154 which holds the secondary arm portion 150 at a predetermined angle relative thereto for the purpose of guiding the stack of cartridges in vertical movement within the magazine chamber.

The stop 154 is a projection which, when the primary arm portion 134 has risen a predetermined amount, contacts the bottom rear surface of the secondary arm portion (which up to this time has been "free" and under no spring tension). Spring tension is now applied to the secondary arm portion. At about this point, the hump 135 on the primary arm portion no longer completely supports the cartridges. Support of the remaining cartridges in the magazine is now taken over by the secondary arm portion.

The primary arm portion of the follower serves as a closure means for the magazine when the firearm is empty, as shown in Fig. 8.

On the uppermost face of the secondary arm portion 150 is a vertically extending medial guide and supporting rib 156 which may be formed integral with or may be otherwise suitably attached to said secondary arm portion so as to give it a generally inverted T shape.

The rib 156 moves vertically within the magazine chamber and is normally biased vertically upwardly as the follower so moves. With no cartridges in the magazine, the rib 156 bears upwardly against the bolt as in the Mauser type of rifle and as shown in Fig. 9.

The medial rib 156 functions to stack the cartridges

in the well-known staggered relation within the magazine chamber as will be hereinafter explained.

When the magazine is fully loaded, the primary and secondary arm portions of the follower are disposed adjacent to or below the lower loading port 130 and the primary arm portion engages the lowermost of the cartridges C of the stack thereof and presses same upwardly.

A magazine follower spring 136 is of the mousetrap type and has a midsection disposed beneath the primary arm portion 134 and has opposite end portions which enclose the pin 142 on opposite outer sides of the trigger guard 119 and within the upwardly extending side-walls 141 of the bottom floor member 140.

A modified form of spring defined as a flat Mauser type magazine spring generally indicated by 143 is shown in Fig. 14. Same may be used in lieu of the mousetrap type of spring shown in Fig. 6.

The upper end of the spring which presses upwardly is retained to the primary arm portion 134 by being slid underneath a projection 145 on the lower side of the primary arm portion 134.

The lower end of the spring which presses downwardly is retained by a projection 145 on the upper side of the bottom floor plate.

When this type magazine spring is used in the manner shown in Fig. 14, the bottom loading feature of the magazine is reduced by one cartridge owing to the fact that the flat spring restricts the downward movement of the follower hinge joint which occurs as the cartridges are being pushed into the loading port 130.

The last cartridge may however be placed in the magazine from the top, as is conventional, with Mauser type firearms.

In other words, the total capacity of the magazine is not reduced but the number of cartridges that can be loaded from the bottom is reduced by one.

The primary arm portion is biased under spring loading to act upon the follower in such manner as to urge the latter toward its uppermost position in the magazine chamber.

With particular reference to Fig. 11, it will be observed that the magazine chamber is of a width to accommodate a double column of cartridges which are confined within the magazine chamber in interengaging staggered relation.

The medial rib on the secondary arm portion 150 is constructed and arranged to engage, by its apex, the lowermost cartridge in the magazine chamber along the longitudinal side portion thereof so as to cause the said cartridge to be disposed on one or the other side of the magazine chamber wherefore the double column of staggered cartridges is attained.

That is to say, and as those skilled in the art will understand, the cartridge stack is comprised of a plurality of cartridges which may be loaded in seriatim into the magazine chamber with the uppermost, first-to-be-loaded, cartridge disposed in the left or right row, as chance may dictate. The medial rib supportably engages a longitudinal side portion of the cartridge and urges same against the adjacent side wall of the magazine chamber irrespective of whether the cartridge is in the relative left or right row of the cartridge stack being formed. The next-to-be-loaded cartridge automatically assumes a position in the opposite row and so on as the subsequent cartridges are loaded thereinto whereby the two-row interengaging staggered relationship is attained.

The secondary arm portion and the medial rib are so shaped and positioned that when the cartridge stack is disposed within the magazine chamber, the cartridges are so positioned that friction is reduced when the uppermost cartridge of the stack is moved through the upper port and forwardly relative to the receiver during the operation of chambering the same into the barrel wherefore the said cartridge is raised to a centered position relative to the barrel chamber.

The cartridges of the stack thereof are confined within the magazine chamber by the side walls of the magazine to exert lateral pressure upon the sides of the cartridge stack thereby retaining the cartridges in the two-row interengaging relation shown and described.

The inner surface of the follower and the surfaces of the medial rib are conformed to such a shape as to permit the free passage of the base portion of the lowermost cartridge upon discharge thereof from the magazine chamber.

No specific number of cartridges need be loaded into the magazine before the same is rendered operable.

Conceivably the cartridges may be stacked in a single row, or in a double row of staggered cartridges, or in a double row converging into a single row.

The bottom floor plate member 140 conceivably may be omitted without affecting the function of the magazine. Were it eliminated, the design of the magazine follower spring 136 would require slight modification as, in the form shown in Figs. 4-14, the member 140 serves to retain one end of said spring 136.

Additionally and if desired, in Fig. 6, a gate 160 may be provided which is fixed to the receiver as by a screw 162 so as to provide a downwardly depending free end portion 161 which by its own spring tension covers the port 130 to prevent ingress therethrough when the breech bolt is rearward, thus functioning as a port shutoff. A lifter 164 is fixed to the receiver as by a pin 166 or the like and is provided at one end with a lifter tail 168 which may be cammed by the breech bolt handle as same is turned downwardly when the breech bolt is in the closed position, as is well-known. As the lifter tail is cammed by the breech bolt handle, the lifter functions to lift the gate away from its blocking position in front of the port 130. The lifter tail additionally functions as a detent to hold the breech bolt closed when in the firing or battery position.

In Fig. 6, the gate is shown as being in the up position, with the breech bolt in the closed position.

In Fig. 8, the gate is shown as being in the down position so as to illustrate the function of the port shutoff in blocking the loading port into the magazine, with the breech bolt in the open position.

The gate, as disclosed herein, is more or less a basic type of gate which is adaptable particularly for bolt action type rifles. In the case of a lever action or straight pull type rifle, the gate would be basically the same but would be somewhat modified in structure.

In Fig. 7, I have illustrated the feature of unloading the cartridge chamber by the act of penetrating the thumb of the operator into the port 130 in the side of the stock 118.

In operation, with the magazine empty, the magazine follower is in its most upward position, as shown in Fig. 8. With the breech bolt closed, the point of a cartridge C may be pressed against the follower, which is pivoted on the magazine follower arm pivot pin, and pushed into the magazine against the tension of the magazine follower spring. After the first cartridge is fully in the magazine, the loading operation may be repeated with other cartridges until the magazine is fully charged.

Referring now to Figs. 15 and 16, I have shown the breech section of a shotgun wherein a shell S is illustrated as being loaded into the magazine chamber and another shell S is represented as already loaded in the magazine chamber, of another form of my invention.

Herein 210 represents the barrel, 212 the receiver, 214 the breech bolt slidably receivable within the receiver, 215 the bolt handle, 218 the stock, 219 the trigger, and 219' the trigger guard.

A magazine chamber is provided within the receiver, as in the form hereinabove described, and comprises a walled vertically disposed opening which extends into the receiver. The upper end of the magazine chamber is open and communicates with the breech bolt chamber.

The lower end of the magazine chamber is likewise open and is provided with a bottom floor plate member 240. A follower arm pivot pin 242 extends transversely through the side walls 324 of the magazine.

5 The magazine chamber includes a forward wall 322, spaced opposite side walls 324 and 324 and a rearward wall 326. The forward and rearward walls, arranged as shown, serve to prevent the rim of the lowermost shell from getting ahead of the rim of the shell thereabove.

10 The primary arm portion 234 of the follower has a bend or hump 235 intermediate its opposite ends, as shown in Fig. 15.

The secondary arm portion 250 of the follower is T shaped in plan view and the top of the T contains the hinge pin connecting it to the follower arm 234.

The front end of the member 250 is narrowed to enable it to enter a vertical slot cut centrally in the forward wall 322 which enables the follower to repose about as shown in Fig. 15 when the magazine is fully charged.

25 A retaining clip 245 is provided on the bottom of the member 234 and serves to retain the mousetrap type spring 236 in place. The lower front ends of the spring are straight and lie flat on the bottom of the magazine.

The invention is not limited in its application to the details of construction and arrangement of parts illustrated in these drawings, since the invention is capable of other embodiments. Here, I have illustrated an example of two embodiments of the invention wherein the parts are combined and arranged in accordance with two modes which I have devised for the practical application of the principles of the invention. It will be understood however that other changes and alterations are contemplated and that other embodiments may be utilized within the scope of the claims, without departing from the basic principles and the contemplated scope of the present invention and that no limitations are to be implied from the foregoing specific description.

30 It is to be further understood that the phraseology or terminology employed herein is for the purpose of description and not of limitation.

35 From the foregoing, the construction and operation of the device will be readily understood and further explanation is believed to be unnecessary. However, since numerous modifications and changes will readily occur to those skilled in the art, it is not desired to limit the invention to the exact construction shown and described and limitation of this invention should be made only as determined by a proper interpretation of the terms used in the subjoined claims.

40 It will be understood by those skilled in the art that the object of the invention may be attained by use of constructions different in certain respects from those disclosed without departing from the underlying principles of the invention. Various suitable modifications and variations in structural changes may be made without departing in any way from the spirit of the invention. I therefore desire by the following claims to include, within the scope of my invention, all such suitable variations, modifications and equivalents by which substantially the results of my invention may be obtained through the use of substantially the same or equivalent means.

45 Without further analysis, the foregoing is intended to so fully reveal the gist of my invention that others can, by applying current knowledge, readily adapt it for various applications without omitting features which, from the standpoint of prior art, fairly constitute essential characteristics of the generic or specific aspects of this invention, and therefore, such adaptations should and are intended to be comprehended within the meaning 50 and range of equivalence of the claims below.

What it is desired to claim and secure by Letters Patent of the United States is:

1. In a firearm, including a receiver and a breech bolt and barrel, the improvement comprising, a vertically disposed magazine extending below the receiver for the loading of the cartridges in seriatim thereinto through a lowermost cartridge loading port and for the storage of a stack of cartridges therein preparatory to the feeding of the same therefrom in seriatim to the breech of the barrel through an uppermost cartridge discharge port, a follower including a vertically movable primary follower arm portion pivotally mounted at the rearward end of said magazine adjacent and below the horizontal plane of the lowermost cartridge loading port and a secondary arm portion pivotally connected to the primary arm portion, said follower being movable vertically in line with the stack of the cartridges, said follower being disposed beneath and embraceable with the lowermost of the cartridges of the stack thereof, said spring means having a capacity for imparting an upwardly directed force to the cartridges of the stack thereof in line with the vertical axis of the stack as the cartridges are held in storage position and are successively discharged through the uppermost cartridge discharge port for chambering purposes, a hump on said primary follower arm portion bearing against the lowermost of the cartridges of the stack thereof with said spring means urging said primary follower arm portion upwardly, said secondary follower arm portion being urged upwardly for acting on the lowermost of the cartridges of the stack thereof when the magazine is partially full by a projection protruding outwardly from said primary follower arm portion and bearing on said secondary follower arm portion.

2. In a firearm, including a receiver and breech bolt and barrel, the improvement comprising, a magazine for the loading of the cartridges in seriatim thereinto through a cartridge loading port and for the storage of a stack of cartridges therein preparatory to the feeding of the same therefrom in seriatim to the breech of the barrel through cartridge discharge port, a follower pivotally mounted at the rearward end of said magazine adjacent and below the horizontal plane of the loading port and movable vertically toward and away from the discharge port, said follower being disposed beneath and embraceable with the lowermost of the cartridges of the stack thereof, spring means for imparting an upwardly directed force to the cartridges of the stack thereof, and a loading port shut-off including, a gate having a forward end fixed to the receiver and a rearward end extending downwardly for normally blocking ingress through the loading port when the breech bolt is in the rearward open position, and a lifter pivotally mounted on the receiver and having a rearward lifter tail portion and a forward elevator portion, the tail portion being cammable downwardly by the breech bolt for lifting said gate away from its covering position when the breech bolt is in its forward position.

3. In a firearm, including a receiver and breech bolt and barrel, the improvement comprising, a vertically disposed magazine extending below the receiver for the loading of the cartridges in seriatim thereinto through a lowermost cartridge loading port and for the storage of a stack of cartridges therein preparatory to the feeding of the same therefrom in seriatim to the breech of the barrel through an uppermost cartridge discharge port, the lowermost cartridge loading port of said magazine being located rearwardly and in the lower portion there-

of, a follower including a vertically movable primary follower arm portion pivotally mounted at the rearward end of said magazine adjacent and below the horizontal plane of the lowermost cartridge loading port and a secondary arm portion pivotally connected to the primary arm portion, said follower being movable vertically in line with the stack of the cartridges, said follower being disposed beneath and embraceable with the lowermost of the cartridges of the stack thereof, said spring means having a capacity for imparting an upwardly directed force to the cartridges of the stack thereof in line with the vertical axis of the stack as the cartridges are held in storage position and are successively discharged through the uppermost cartridge discharge port for chambering purposes, a hump on said primary follower arm portion bearing against the lowermost of the cartridges of the stack thereof with said spring means urging said primary follower arm portion upwardly, said secondary follower arm portion being urged upwardly for acting on the lowermost of the cartridges of the stack thereof when the magazine is partially full by a projection protruding outwardly from said primary follower arm portion and bearing on said secondary follower arm portion.

4. In a firearm, including a receiver and breech bolt and barrel, the improvement comprising, a magazine extending below the receiver for the loading of the cartridges in seriatim thereinto through a cartridge loading port and for the storage of a stack of cartridges therein preparatory to the feeding of the same therefrom in seriatim to the breech of the barrel through a cartridge discharge port, a follower including a vertically movable primary follower arm portion pivotally mounted at the rearward end of said magazine adjacent and below the horizontal plane of the cartridge loading port and a secondary follower arm portion pivotally connected to said primary portion, said follower being movable vertically in line with the stack of the cartridges, said follower being disposed beneath and embraceable with the lowermost of the cartridges of the stack thereof, spring means imparting an upwardly directed force to the cartridges of the stack thereof in line with the vertical axis of the stack as the cartridges are held in storage position and are successively discharged through the cartridge discharge port, a hump on said primary portion bearing against the lowermost of the cartridges of the stack thereof with said spring means urging said primary portion upwardly, said secondary portion being urged upwardly for acting on the lowermost of the cartridges of the stack thereof when the magazine is partially full by a projection protruding outwardly from said primary portion and bearing on said secondary portion.
